UNITED STATES PATENT OFFICE.

CHARLES T. SCHEOYER, OF SIOUX FALLS, SOUTH DAKOTA, AND ELWOOD C. DESSEM,
OF WORTHINGTON, MINNESOTA.

CLEANING DEVICE.

Application filed January 8, 1927. Serial No. 159,942.

This invention relates to a cleaning device and has relation more particularly to a device of this kind especially designed and adopted for use in connection with windshields and the like, and it is an object of the invention to provide a device constructed in a manner whereby moisture, frost, ice and the like forming upon such shield or kindred surface may be readily removed in order to assure a clear vision.

Another object of the invention is to provide a device of this kind comprising a blade member supported in a manner to have the knife edge of such member in close contact with the surface to be cleansed and wherein such blade member has its working marginal portion formed in a manner to readily yield to compensate for any inequalities or irregularities which may be in the surface over which the device traverses.

An additional object of the invention is to provide a device of this kind of a scraper type and which may be readily and effectively applied in working position with respect to a wiper of a conventional type.

The invention consists in the details of construction and in the combination and arrangement of the several parts of our improved cleaning device whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawings, wherein:

Figure 1 is a fragmentary elevational view illustrating a cleaner constructed in accordance with an embodiment of our invention and in applied position;

Figure 2 is a view in side elevation of the structure illustrated in Figure 1 with the associated portions of the windshield shown in section;

Figure 3 is a sectional view taken substantially on the line 3-3 of Figure 1;

Figure 4 is a view similar to Figure 2 illustrating a further embodiment of our invention.

As disclosed in the accompanying drawings, 1 denotes the upper frame member of

a windshield structure and with which is associated in a well known manner the glass panel 2. Disposed through the member 1 at a desired point thereon is a shaft 3 provided at one end portion with an operating member 4 whereby the shaft 3 may be rotated or rocked as desired.

The opposite end portion of the shaft 3 has fixed thereto an end portion of a resilient or spring member 5, herein disclosed as disposed on substantially a sigmoidal curvature and which has its opposite or outer end portion operatively engaged, as at 6, with the back or head 7 of a conventional wiper for a windshield or the like.

Our improved cleaner comprises a channel head 8 which is adapted to receive the wiper 7 or the like and which is provided along its sides with the outwardly diverging flanges 9 disposed on desired angle and to each of which is spot welded, as at 10, or otherwise attached a blade 11. Each of the blades 11 is preferably co-extensive in length with the associated flange 9 and has its outer marginal portion extending beyond the outer marginal portion of the flange 9 so that the cutting edge of the blade will have close contact with a surface of the panel 2. This blade 11 is preferably thin and possessing a certain degree of yieldability or flexibility and its outer or working marginal portion at points spaced longitudinally thereof is slotted, as at 12, in order to compensate for such inequalities or irregularities which may occur in the surface of the panel 2 over which the blade travels, thus assuring effective cleaning action of the blade.

The resiliency of the member 5, or arm as it may be called, exerts sufficient pressure upon the device 7 and the applied member 8 to maintain the diverging blades 11, and more especially the cutting edges thereof in close contact with a surface of the panel 2 so that as the blades swing across such panel upon turning or rocking of the shaft 3 such surface of the panel will be effectively cleansed of moisture, frost or the like which may collect thereon, thus assuring a place of clear vision through the panel 2.

As is particularly illustrated in Figure 3, it is to be noted that the intermediate portion 12 of the member 8 is interposed between the wiper 7 and the panel 2 so that the

tension of the member or arm 5 plus the opposed tension resulting in the contact of the blades 11 with the panel 2 effectively maintains the member 8 in applied or working position with respect to the wiper 7. However, under certain conditions it is desirable that the holding or binding screws 14 be employed, said screws being carried by the opposite end portions of the member or body 8 and having effective engagement with the wiper 7 or kindred element to which the body or member 8 may be applied.

In the embodiment of our invention as illustrated in Figure 4, cleaning elements A and B are arranged at opposite sides of and in working engagement with the panel 2'. These elements A and B are constructed and mounted substantially the same as the embodiment of our invention as hereinbefore described although the member B necessarily does not have to be associated with a wiper or kindred element but has the arm or member 5' directly engaged therewith. This member or arm 5' at one end is provided with a sleeve 15 through which is disposed the shaft 3', said sleeve when it is desired to have the members A and B work in unison is locked to the shaft 3' by a binding screw 16 or otherwise as may be preferred. With the sleeve 15 locked to the shaft 3' upon turning movement of the shaft 3' the cleaning members A and B will have unitary movement across the opposed faces of the panel 2'. The use of the two cleaning members is particularly desirable in such localities wherein dense fogs are encountered and which fogs have a tendency to cloud both faces of the panel.

When it is desired to use only the member A, the sleeve 15, upon proper manipula-

tion of the screw 16, is freed from turning movement with the shaft 3' and, if desired, the member B may be supported in a lifted or other desired inoperative position.

From the foregoing description it is thought to be obvious that a cleaning device constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as hereinafter claimed.

We claim:—

1. A scraper attachment for a windshield wiper comprising a body directly engageable with the wiper and interposed between the wiper and the windshield, said body having outwardly diverging flanges extending therealong, and blades carried by said flanges, said blades being adapted to have contact with the windshield.

2. A scraper attachment for a windshield wiper comprising a body directly engageable with the wiper and having outwardly diverging flanges extending therealong, and blades carried by said flanges, said blades being adapted to have contact with the windshield, said body being provided with a channel to receive the wiper.

In testimony whereof we hereunto affix our signatures.

CHARLES T. SCHROYER.

ELWOOD C. DESSEM.
